UNITED STATES PATENT OFFICE.

COLUMBUS MCPHERSON, OF DA CONO, COLORADO.

GRAB-HOOK.

1,243,617.

Specification of Letters Patent. Patented Oct. 16, 1917.

Application filed October 23, 1916. Serial No. 127,262.

To all whom it may concern:

Be it known that I, COLUMBUS MCPHERSON, citizen of the United States, residing at the city of Dacono and State of Colorado, have invented certain new and useful Improvements in Grab-Hooks; and I do declare the following to be a full, clear, and exact description of the invention, such as will enable others skilled in the art to which it appertains to make and use the same, reference being had to the accompanying drawings, and to the characters of reference marked thereon, which form a part of this specification.

15 The present invention relates to improvements in well appliances and pertains more particularly to an improved grab hook adapted for use in withdrawing articles from the bottom of a well.

20 It frequently happens in the installation and use of pumps in a well, that the sucker rod becomes broken at some point below the surface of the ground and drops to the bottom from which position it is extremely difficult to recover. The principal object 25 of the present invention is to provide an improved attachment, which may conveniently be termed a grab hook and which can be removably secured to the lower end of the inner pipe section and lowered into operative position to engage the dislodged part 30 of the broken member. A further object of the invention consists in providing this member with a loosely carried gripping device which engages the broken rod or other member and firmly clamps it until the part 35 on which it is carried has been sufficiently elevated above the surface of the ground.

With these and other objects in view the 40 invention consists in the combination and arrangement of parts more fully set forth in the following specification, illustrated in the accompanying drawing and more particularly pointed out in the appended 45 claims.

In the drawings:

Figure 1 is a vertical transverse sectional view taken through the lower portion of a well and pump of the deep well type.

50 Fig. 2 is a similar view showing one embodiment of the present invention applied to the lower end of the pump cylinder, the sucker rod of the pump being shown as broken and dropped to the bottom of the well.

55 Fig. 3 is a view similar to Fig. 2, but

showing the parts in different relative positions, and

Fig. 4 is a transverse horizontal section of the invention, taken on the line 4—4, looking downward in the direction of the arrows.

Referring now to the drawing, in Fig. 1 is shown a lower fragmental view of a deep well the cylindrical casing 5 of which is 60 provided with an end strainer member 6. Within the well casing 5 is the pump cylinder composed of a plurality of connected sections, the lowermost 7 of which carries the intake check valve 8. The pump valves 70 9 are secured to the lower end of the pump or "sucker" rod 10. It not infrequently happens that this rod breaks and generally at a place considerably below the surface of the ground. The result is, the weight of 75 the loosened portion of the rod crashes downwardly through the lower end of the pump breaking away the valve structure 8. Great difficulty has been experienced in extricating such a broken part from the 80 bottom of a deep well. According to the present invention the pump casing is withdrawn and a cylindrical member 11 is screw-threaded onto the lower pump section as shown in Figs. 2 and 3. This cylindrical member 11 is hollow and its bottom edge 85 is outwardly flared as shown at 12 to form a bell like end. Rigidly carried at the inner side of the casing member is a depending hook member 13. A pivoted gripping 90 member 14 is provided within the cylindrical member 11 and is formed with a pair of outwardly projecting oppositely disposed lugs 15 which engage slightly elongated slots 16 in the walls of the casing 11. This member 14 is formed with its outer edges 95 conforming to the contour of the inside of the casing 11 and is of sufficient area to extend approximately two-thirds of the way across the casing. Its outer edge 17 which 100 is sharpened or beveled as in Fig. 4 is slightly wider than the cross section of the casing 11 at this point and hence it is impossible for this member to drop into the horizontal position. The pump casing 7 with the member 11 applied thereto is inserted in the well until the depending hook 13 is lowered sufficiently to engage the broken part of the sucker rod 10. The well 105 casing is then turned in either direction whereupon the hook 13 will contact with 110 and move the upper end of the broken rod

into the path of the lower bell 12 of the casing 11. The casing 11 is then lowered until the upper end of the rod 10 passes upwardly into the cylindrical member and assumes approximately the position illustrated in Fig. 3. It will there be seen that the rod 10 causes the pivoted gripping member 14 to be swung slightly upwardly and hence any upward movement exerted on the well casing 7 will cause the member 14 to grip one edge of the pipe or rod stem 10 while the opposite side of the stem 10 will at the same time be clamped against the inner wall of the casing 7 or member 11 as the case may be. The pump casing may now be steadily withdrawn and the rod 10 or the broken portion thereof will be brought up to the surface of the ground.

It will thus be seen that a very simple, cheap and effective means is provided for extricating from the bottom of a deep well a broken part which otherwise might cause serious delay and possible abandonment of the well.

Having described my invention what I claim is:

1. The combination with the pump casing

of a well, of a grab hook removably carried at the lower end of the casing and depending therefrom for facilitating the removal of an obstruction at the well bottom.

2. The combination with the pump casing of a well, of a hollow section removably carried thereon, having a grab hook depending therefrom and a pivoted gripping member co-operating therewith for facilitating the removal of an obstruction at the well bottom.

3. The combination with the pump casing of a well, of a hollow cylindrical section removably carried thereon, said section having a lower bell shaped end, a depending grab hook rigidly carried by said section and a pivoted gripping member within said section and co-operating with said grab hook to facilitate the withdrawal of an obstacle from the well bottom.

In testimony whereof I affix my signature, in presence of two witnesses.

COLUMBUS McPHERSON.
